UNITED STATES PATENT OFFICE.

GEORG GRABE, OF NIKOLASSEE, NEAR BERLIN, GERMANY, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed October 8, 1921, Serial No. 506,424, and in Germany October 11, 1920.

The present invention relates to telephone systems and more particularly to a circuit arrangement which serves to prevent wrong connections in automatic or semi-automatic telephone installations. Certain of the selecting devices used for making the connections are set on a line or group of lines by means of numeral current impulses emitted by a sending instrument. In the latter case 10 the selecting devices automatically seek a disengaged line. Selectors are also provided which, like the pre-selectors, exercise a free selection. Now the contingency may arise that numeral impulses are sent out 15 from the sending instrument before the selecting device in front of the numerical switch has completed a free selection which it is executing. In such a case the numerical switch will only receive a portion of the 20 series of impulses, and will, in consequence, be set on a line or group of lines other than that desired.

To obviate this drawback according to the invention the selecting devices are provided 25 with means which prevent the completion of a partly established connection in the event of a series of numerical impulses being emitted from the calling station before the automatic trunk or free selection is completed. The circuits are preferably so arranged that, when the first numeral impulse comes into operation, the selecting device that is in the act of setting comes to a standstill and the testing is prevented, whilst at 30 the same time a signal (e. g. a buzzer signal) is transmitted to the calling subscriber.

It may frequently happen that mechanical defects or contamination may retard the setting action of the selecting device exercising 40 free selection. To enable immediate identification of the selecting devices that are working properly, the circuits are arranged to prevent the release of the selecting devices that have already been set, this being prefer- 45 ably effected at the moment the first numeral impulse comes into action. At the same time a control signal is switched on, which indicates the selecting device into which numeral impulses have gained access before 50 the free selection has been completed. By preventing the release of the already set selecting devices, the calling subscriber's line can also be identified at the same time, so

that, if the selectors are in good order, the impulse sender can be examined, since it may 55 cause faults by running off too quickly.

The drawing illustrates two different embodiments of the invention, a selector being represented in both cases. The invention is not, however, restricted to selectors, since 60 each pre-selector may be provided with a switch device preventing the completion of the connection in the event of numeral impulses being emitted before free selection has been completed. 65

Fig. 1 shows a selector GW, which may be mechanically of the well known Strowger type. The circuits in this figure illustrate one embodiment of the invention.

Fig. 2 shows a selector GW' which is similar to the selector GW except that the circuits have been slightly altered in order to illustrate a second embodiment of the invention. 70

The switch arrangement according to Fig. 75 1 operates in the following manner:

When the selector GW is engaged, the relay C operates through the *c*-conductor, winding I of C, 7_k, earth, so that the contacts 1_c, 10_c, 15_c and 32_c of this relay are 80 closed. The closing of the contact 1_c connects the relay C with a holding circuit dependent on the contact 2_m of the release magnet M. The switching through of the speaking leads in the selecting devices situated in front of the selector GW, through the subscriber's line, caused the impulse relay A to be switched on followed by the switching on of the slow-acting release relay V₁ at the contact 3_a. The closure of 85 contacts 1_v closed a multiple path from ground by way of 2_m and resistance R to test lead *c* to make this lead busy to other selecting devices. If numeral impulses be emitted from the caller's instrument the impulse relay A is rendered intermittently dead in accordance with the impulses. Hence, each time the contact 5_a of the relay A is closed, the lifting magnet H is energized as follows: earth, 32_c, 26_p, 4_{v₁}, 5_a, V₂, 100 6_n, H, battery, earth. In this manner, the selector is lifted to the desired group of lines in accordance with the number of the numeral impulses. At the first lifting movement the contact 7_k was opened, whilst 105 the contacts 8_k and 9_k were closed. During

the series of impulses for lifting the selector, the relay V_2 remains energized, and only drops when the contact 5_a has remained open for some time after the series of impulses has come to an end. When the relay V_2 drops, its contact 12_{v_2} closes, so that the rotary magnet D is energized through: earth, 10_r , 11_{v_1} , 12_{v_2} , 13_p , D , 8_k , battery, earth.

The selector is now set in rotary motion and begins to test. If it finds a disengaged line, the testing relay P operates through: earth, battery, 14_{v_1} , 15_c , windings II and I of P , c_1 , C_1 , earth. The testing relay operates, short circuits its high-resistance winding II at the contact 16_p , and thus blocks the engaged line against engagement by another selecting device. Furthermore, the relay P opens the circuit of the rotary magnet D at the contact 13_p , and the circuit of the release magnet M at the contact 17_p ; and, in addition the speaking leads are switched through—the impulse relay A being shut out—by opening the contacts 18_p and 19_p and closing the contacts 20_p and 21_p . The opening of the contact 26_p prevents the switching on of the winding II of the relay C . The impulse relay A , which drops when the contacts 18_p and 19_p are opened, opens its contact 3_a , so that the slow acting relay V_1 is also rendered dead and closes its contact 22_{v_1} .

The release of the selecting device on the termination of the conversation is effected in known manner by interrupting the current through the lead c_1 . The falling relay P completes, via 17_p , the circuit for the release magnet M , since the contact 22_{v_1} , was already closed, in the above described manner, in switching through the speaking leads. The release magnet M operates, interrupts the current through the lead c by opening the contact 2_m , and releases the selector.

The case will now be considered in which numeral impulses have been emitted while the selector is still seeking a disengaged line. At the first rotary movement of the selecting device the rotary contact 6_n is opened and the rotary contact 23 closed. If the relay A be de-energized by impulses during the rotation of the selecting device, then, as soon as the contact 5_a is closed by the first impulse, the winding II of the relay C is energized by way of the contact 23_a . This winding is in differential connection with the winding I. The windings counteract each other and the relay C becomes dead. When the relay C drops, its contacts 1_c , 10_c , 15_c and 32_c are opened, thus interrupting the holding circuit through winding I of the relay C , stopping the selecting device, preventing the testing, and switching off the winding II of C . The switching off of the winding II of C is necessary in order to avoid re-energizing of C by the second im-

pulse, since when this impulse occurs the winding I is no longer energized. Moreover an “engaged” buzzer BS is connected to the winding III of the impulse relay A at the contact 24_c of relay C , through the rotary contact 25_n , which is closed on the first rotary movement. The subscriber hears the “engaged” signal. When he hangs up the receiver, the impulse relay A becomes dead, opening its contact 3_a so that the slow-acting relay V_1 drops and closes its contact 22_{v_1} . This switches on the release magnet M which releases the selecting device.

The switch arrangement illustrated in Fig. 2 corresponds in general to the arrangement in Fig. 1, but differs therefrom in that the selecting device is not released by hanging up the receiver at the calling instrument. With this object, in the arrangement according to Fig. 2, the circuit of the release magnet M is also influenced by a contact 28_c of the relay C . If the relay C is de-energized in the above manner while the selecting device is seeking a disengaged line, the contact 28_c opens, and consequently the release magnet M cannot be energized even after the closing of the contact 22_{v_1} . Moreover, on the dropping of the relay C , a control lamp CL is switched on through the contact 29_{v_1} of the relay V_1 , rotary contact 30_n and contact 31_c of relay C , thus indicating to the exchange operator which of the selecting devices has not been released. Owing to the non-release of the selecting device, the current through the incoming lead c is not interrupted, so that the pre-arranged selecting devices remain set.

What I claim and desire to secure by Letters Patent is:—

1. In a telephone system, a switch, wipers for said switch, means for transmitting a set of impulses to said switch for directly operating said wipers, means for automatically operating said wipers, means controllable from a calling line for releasing the switch, and means responsive to another set of impulses transmitted to said switch before the second named means has completed its operation for locking said switch in operated position independent of control from the calling line.

2. In a telephone system, a switch, wipers for said switch, means for transmitting a set of impulses to said switch for directly operating said wipers, means for automatically operating said wipers, means controllable from a calling line for releasing the switch, and means responsive to another set of impulses transmitted to said switch before the last named means has completed its operation for locking up said switch independent of control from the calling line and for operating a signal.

3. In an automatic telephone system, a se-

lector, relays for operating the selector, a group of line terminals accessible from the selector, remote control means for causing the operation of the relays to set the selector into hunting relation to the line terminals and seize the first idle one encountered, and relay means comprising only said relays for disabling the selector from seizing responsive to the control means being operated 10 while the selector is hunting.

4. In an automatic telephone system, a wiper selector, relays of the selector, a group of line terminals accessible from the selector, remote control means for causing the operation of the relays to set the selector into hunting relation to the line terminals and seize the first idle one encountered, and relay means comprising only said relays for disabling the selector from seizing responsive 15 to the control means being operated while the selector is hunting.

5. In an automatic telephone system, a wiper selector, relays of the selector, a group of line terminals accessible from the selector, remote control means for causing the operation of the relays to set the selector into hunting relation to the line terminals and seize the first idle one encountered, and relay means comprising only said relays for 20 disabling the selector from continuing its hunting operation responsive to operating the control means while the selector is hunting.

6. In an automatic telephone system, a wiper selector, relays of the selector, a group of line terminals accessible from the selector, remote control means for causing the operation of the relays to set the selector into hunting relation to the line terminals and seize the first idle one encountered, and means for disabling the selector from continuing its hunting operation responsive to operating the control means while the selector is hunting. 35

7. In an automatic telephone system, a wiper selector, relays of the selector, a group of line terminals accessible from the selector, remote control means for causing the operation of the relays to set the selector into hunting relation to the line terminals and seize the first idle one encountered, and means responsive to the control means for stopping the hunting operation without restoring the selector. 45

8. In an automatic telephone system, a calling line, a selector, relays for operating the selector, a group of line terminals accessible from the selector, control means operated over the calling line for causing the operation of the relays to set the selector into hunting relation to the line terminals and seize the first idle one encountered, and relay means comprising only said relays for disabling the selector from seizing responsive 55

to the control means being operated 65 while the selector is hunting.

9. In a telephone system, a calling line, a selector, relays of the selector, a group of line terminals accessible from the selector, directive control means on the calling line 70 for operating certain of the relays to set the selector with selective relation to the group, means for causing certain of the relays to thereafter operate the selector in hunting relation with the group and seize 75 the first idle terminal found, and relay means comprising only said before operated relays for disabling the selector from seizing responsive to the control means being operated while the selector is hunting. 80

10. In a telephone system, a calling line, a selector, relays of the selector, groups of line terminals accessible from the selector, directive control means on the calling line for operating certain of the relays to set the selector with selective relation to a desired 85 group, means for causing certain of the relays to thereafter operate the selector in hunting relation with the group and seize the first idle terminal found, and relay 90 means comprising only said before operated relays for disabling the selector from seizing responsive to the control means being operated while the selector is hunting.

11. In a telephone system, a calling line, 95 a selector, relays of the selector, a tone source, a group of line terminals accessible from the selector, automatic control means for causing the operation of the relays to set the selector into hunting relation to the line 100 terminals and seize the first idle one encountered, and relay means comprising only said relays for applying the tone source to the calling line responsive to the control means being operated while the selector is hunting. 105

12. In a telephone system, a calling line, a selector, relays of the selector, a tone source, a group of line terminals accessible from the selector, automatic control means for causing the operation of the relays to set the selector into hunting relation to the line terminals and seize the first idle one encountered, and relay means comprising only said relays for applying the tone source to the calling line and for disabling the selector 110 from seizing responsive to the control means being operated while the selector is hunting. 115

13. In a telephone system, a calling line, a trunk line terminating in an automatic switch having a primary and a secondary 120 movement, trunk lines accessible to said switch, means controlled from said calling line for seizing said trunk line and for causing said switch to operate successively in its primary and secondary movements to select 125 an idle one of said trunk lines, means for sending impulses over said calling line, and means operative responsive to said impulses

being sent before said switch has connected with an idle trunk for placing a busy tone on said calling line and for stopping the secondary movement of said switch.

14. In a telephone system, a calling line, a trunk line terminating in two motion automatic switch, trunk lines accessible to said switch, means controlled by said line for seizing said trunk line and for causing said switch to operate in its two motions successively to select an idle one of said trunk lines, means for sending impulses over said calling line, and means operative responsive to said impulses being sent before said switch has connected with an idle trunk for stopping the movement of said switch.

15. In a telephone system, a plurality of lines, an automatic switch, trunks accessible to the switch, means for extending a connection from a calling line to the switch, means for transmitting a group of digit impulses to the switch, means in the switch responsive to the digit impulses for operating the same, means responsive to the cessation of the group of impulses for causing the switch to hunt for a trunk, and means effective responsive to another group of impulses being transmitted to the switch prior to the cessation of the hunting movement of the switch for maintaining the connection between the calling line and said switch independent of control over the calling line to enable the attendant to identify the calling line.

16. A telephone system wherein any one of a plurality of lines may be connected to any one of a plurality of automatic switches, trunks accessible to each of the switches,

each switch including means for selecting an idle trunk, said means comprising means controlled by a group of digit impulses to select a group of lines and automatically controlled responsive to the cessation of the group of impulses to select an idle trunk in the group, and means effective responsive to a subsequent group of impulses transmitted to the switch prior to the termination of the automatic movement of the switch for maintaining the connection between the calling line and said switch independent of control over the calling line to enable the attendant to identify the particular calling line and the particular switch.

17. A telephone system wherein any one of a plurality of lines may be connected to any one of a plurality of automatic switches, trunks accessible to each of the switches, each switch including means for selecting an idle trunk, said means comprising means controlled by a group of digit impulses to select a group of lines and automatically controlled responsive to the cessation of the group of impulses to select an idle trunk in the group, and means effective responsive to a subsequent group of impulses transmitted to the switch prior to the termination of the automatic movement of the switch for maintaining the switch operated independent of control over the calling line, to enable the attendant to identify the switch.

In witness whereof, I hereunto subscribe my name this 14th day of September, A. D. 1921.

GEORG GRABE.
